FIG. 1

FIG. 2

INVENTOR.
H. W. JONES
BY *H. G. Grover*
ATTORNEYS.

UNITED STATES PATENT OFFICE.

HOMER W. JONES, OF LAKEWOOD, OHIO, ASSIGNOR TO NATIONAL CARBON COMPANY.
INC., A CORPORATION OF NEW YORK.

TERMINAL CONNECTION.

1,376,627.

Specification of Letters Patent.

Patented May 3, 1921.

Application filed October 10, 1919. Serial No. 329,833.

To all whom it may concern:

Be it known that I, HOMER W. JONES, a citizen of the United States, residing at Lakewood, in the county of Cuyahoga and State of Ohio, have invented a certain new and useful Improvement in Terminal Connections, of which the following is a full, clear, and exact description.

The present invention relates to an improvement in terminal connections for the carbon electrode of dry cells.

A connection of this kind which is widely used is that shown in U. S. Patent 813,093 to E. C. Henn and is commonly known as the driven dowel terminal. The present terminal and improvements embodied therein utilizes and is especially applicable to the driven dowel construction.

The principal objects of the invention are to decrease the cost, shorten the carbon electrode, improve the appearance and decrease the twisting strain on the dowel.

Additional advantages will appear in the following description of several specific embodiments of the invention, reference being had to the drawings in which:—

Figure 1 is a fragmentary cross section of the construction which at present is the preferred form.

Fig. 2 illustrates a modification.

The construction is illustrated in connection with a dry cell consisting of a zinc container electrode 1 having a paper lining 2, mix 3 and layer of sand 4. In accordance with the present invention I utilize a central carbon electrode 5 which has the upper end below the upper edge of the zinc container. The terminal preferably consists of a driven dowel having a ribbed portion 6 forced into a hole in the upper end of the carbon electrode. The dowel is forced into the electrode so that the upper surface of the shoulder 7 is even with or a little above the upper edge of the zinc can and the threaded stud 8 projects therefrom. A brass cap 9 having a small hole in the top and a flange 12 at the bottom of the skirt 10 is then fitted over the threaded stud, the dimensions of the cap preferably being such that the flange of the depending skirt 10 is in contact with the upper end of the carbon electrode while the top contacts with the shoulder 7. The seal is then poured into the can to fill the upper end which em-

beds and holds the electrode and skirt of 55 the cap securely therein.

The carbon electrode required with this connection is shorter and therefore less expensive than that used with the ordinary driven dowel construction. By embedding 60 the end in the seal the finished cell has a neater appearance and the carbon electrode cannot become loosened. The cap which is made of thin stamped sheet metal is relatively inexpensive. When a nut is applied 65 to the threaded member the cap tends to prevent the dowel from becoming loosened by twisting in a hole due to the application of unnecessary force. This is due to the fact that after the nut is turned down tight 70 against the cap the dowel cannot be twisted without also turning the cap. As the cap is held by the seal an additional means is thus provided resisting any turning of the dowel in the carbon electrode.

In the modification shown in Fig. 2 a driven dowel is utilized having a wide shoulder 11 which replaces the shoulder 7 and cap 9. In this form the end of the electrode is embedded in the seal and the 80 shoulder rests on the upper end of the electrode and projects from the seal.

The forms described appear to be the most simple and satisfactory and further modifications within the scope of the claims 85 and the limits of the invention will not be described in detail.

Having described my invention, what I claim is:—

1. A dry cell comprising a container, a seal in said container, an electrode extending into said container and having its upper end below the upper surface of the seal, said electrode having a bore therein, a dowel having a ribbed portion forced in said bore 95 in retaining engagement with the electrode and a portion projecting from said seal adapted to receive suitable means for attaching a conductor to the projecting portion, and a metallic member located above 100 the upper end of the electrode between the ribbed and projected portions of the dowel, said member having a portion embedded in the seal and an exposed portion adapted to coöperate with said means.

2. A dry cell comprising a container, a seal in the upper end of the container, an electrode extending into said container and hav-

ing its upper end below the upper surface of the seal, said electrode having terminal retaining means, a terminal having a portion in engagement with the terminal retaining means, and a portion projecting from said seal adapted to receive clamping means, and a metallic cap member located above the upper end of the electrode, said cap having a depending skirt in contact with the upper end of the electrode and embedded in the seal, and an exposed top having an opening adapted to permit the terminal member to be passed therethrough.

3. A dry cell comprising a container, a seal in the upper end of the container, a carbon electrode extending into said container and having its upper end below the upper surface of the seal, said carbon electrode having a bore therein, a dowel having a portion

in said bore in retaining engagement with the carbon electrode and a threaded portion projecting from said seal adapted to receive a clamping nut, and a shoulder between said portions, the upper surface of said shoulder being substantially flush with the upper surface of the seal, and a metallic cap member located above the upper end of the electrode, said cap having a depending skirt in contact with the upper end of the electrode and embedded in the seal, and a top resting in the dowel shoulder, said top having an opening adapted to permit the threaded member to pass therethrough, said top projecting from the seal and adapted to serve as a seat for a clamping nut. 35

In testimony whereof, I hereunto affix my signature.

H. W. JONES.
